(57) CLAIM

The ornamental design for a dorsal lower torso and gluteal entertainment plate, as shown and described.

DESCRIPTION

FIG. 1 is a top and side perspective view of a dorsal lower torso and gluteal entertainment plate showing my new design.

FIG. 2 is a top plan view thereof.

FIG. 3 is a bottom plan view thereof.

FIG. 4 is a side elevation view thereof.

FIG. 5 is a sectional view taken along section line 5-5 of FIG. 2, the reverse side being a mirror image thereof.

FIG. 6 is a front view thereof; and,

FIG. 7 is a rear view thereof.

The broken lines in the drawing depict environmental subject matter only and form no part of the claimed design.
